CIGAR PACKAGING MACHINE

Henry H. Wheeler, Newton, Conn., assignor to International Cigar Machinery Company, a corporation of New Jersey

Filed Apr. 7, 1959, Ser. No. 804,742

9 Claims. (Cl. 53—133)

This invention relates to improvements in wrapping machines and more particularly to a packaging machine adapted to enclose articles; such as, cigars in a wrapping material envelope provided with a tear strip to facilitate opening.

Generally cigars are preferably wrapped in transparent wrapping material having a heat energizable coating. To facilitate opening of the envelope thus formed to provide access to the contents, it is desirable to provide a tear strip to be actuated by a user. The present invention is characterized by the utilization of a tear strip web which is of a width coextensive with that of the wrapper material web, and is provided with registering indicia preferably in the form of the regularly recurring cigar band patterns. Both the wrapper web and the tear strip web are fed intermittently along the same line of travel. When the tear strip web has been placed in proper registration with respect to the wrapper web as determined by a photoelectric device, the tear strip web feed is interrupted, and a narrow width of tear strip is severed from the tear strip web and secured preferably, by heat-sealing, to the stationary wrapper web across the entire width thereof. A suitable length of wrapper web with the tear strip properly secured thereon is then delivered to the envelope forming portion of the packaging machine and severed from the web.

It is therefore an object of the present invention to provide a packaging machine for enclosing cigars within a sealed envelope having a tear strip attached thereto to facilitate opening.

It is a further object of the present invention to provide means for supplying a narrow tear strip for attachment to a wrapper material web from a wide band of tear strip web.

It is also an object of this invention to provide a registration device for properly positioning a tear strip on a wrapping material web.

Another object of this invention is to provide in a packaging machine for enclosing cigars within a sealed envelope a tear strip web and a wrapper material web intermittently fed along the same line of travel.

An added object of the present invention is to provide means for registering a printed band web with respect to a wrapper material web severing the leading end band from the band web and heat sealing it to the continuous wrapper web.

Other objects and features of the invention will appear as the description of the particular physical embodiment selected to illustrate the invention progresses. In the accompanying drawings, which form a part of this specification, like characters of reference have been applied to corresponding parts throughout the several views which make up the drawings.

Figure 1 is a side elevation of a wrapping machine constructed in accordance with the invention.

Figure 2 is a sectional side elevation of the wrapping machine shown in Figure 1.

Figure 3 is a plan view of the wrapping machine shown in Figure 1.

2

Figure 4 is a sectional plan view taken on line 4—4 of Figure 2.

Figure 5 is a sectional end elevation taken on line 5—5 of Figure 2.

5 Figure 6 is an end view of the article enveloping and folding mechanism.

Figure 7 is a detailed side elevation of a part of the web feeding mechanism.

10 Figure 8 is a sectional end elevation taken on line 8—8 of Figure 7.

Figure 9 is an enlarged sectional end elevation of the wrapper edge slitting mechanism.

Figure 10 is a fragmentary view of a web from which the individual cigar bands or tear strips are cut, and

15 Figure 11 is a plan view of an individual cigar wrapper blank with an associated cigar band or tear strip.

Referring to the drawings which illustrate a preferred embodiment of the invention, the machine is driven by a gear 20 (Figures 1 and 2) from a suitable source of power (not shown). Gear 20 is mounted on shaft 22 supported in suitable bearings of machine frame 24. The hub of gear 20 preferably is integral with gear 26 which meshes with and drives gear 28 (Figures 2 and 4) keyed to shaft 30 rotatably supported in suitable 25 bearings in frame 24. Gear 28 meshes with and drives gear 32 (Figures 1 and 4) secured to cam shaft 34 rotatably supported in bearings in frame 24. Pulley 36 (Figure 1) mounted on shaft 34 is tracked by belt 38 which runs on and drives pulley 40 (Figures 1 and 3) fixed to shaft 42 supported in suitable bearings in a pair of brackets 44 secured to bed plate 46 adjustably mounted on frame 24. A lower web feed roller 48 (Figure 2) mounted on shaft 42 operates in conjunction with an upper web feed roller 50 mounted on shaft 52. This 30 shaft carries gear 54 which meshes with and is driven by a gear 56 secured to lower feed roller drive shaft 42. Upper feed roller shaft 52 is supported in suitable bearing blocks 58 slidably mounted in vertical slots 60 in brackets 44.

40 The cigar wrapping material; such for example as heat sealable cellophane, is pulled by feed rollers 48 and 50 from a reel (not shown) in form of a web W over the top surface of bed plate 46 where it is guided lengthwise thereacross and over a ramp-like bridge bracket 62 (Fig. 2). The leading end of the web is engaged by

45 a pair of reciprocating gripper fingers generally designated 64 mounted on a pair of parallel spaced horizontally reciprocating rods 66. Rods 66 at their forward ends are secured to a transverse activating bar 68 while the central and rear portion of rods 66 are slidably

50 supported in suitable bearings of the bed plate 46 and in bearing lugs 70 of a bracket 72 respectively. Bracket 72 is mounted on frame 24 of the machine. Transverse bar 68 is provided with an elongated slot or track 74 (Figures 2, 3, 4 and 5) in which is mounted a roller

55 76. Roller 76 is rotatably secured to one end on stud shaft 78 carried by bar 80. Bar 80 is adjustably secured by a set screw 82 (Fig. 3) in a dovetail slot 84 in the hub of gear 86. Gear 86, in turn is rotatably mounted on a crankpin 88 carried by bevel gear 90. Bevel gear 90 is rotatably supported by a hub bearing 92 held by bracket 94 (Figs. 2 and 4) secured to the lower face of gear plate 96. Gear plate 96, in turn is mounted to the bottom side of bed plate 46. Plate 96 has a circular opening which is provided with gear teeth 98 thus

60 forming a stationary, internally toothed gear which engages with the spur gear 86 carried by the crankpin 88 of bevel gear 90. Bevel gear 90 engages with and is continuously driven by a bevel gear 100 keyed to the continuously rotating shaft 30. Thus, since gear 86 on crank pin 88 meshes with teeth 98 of the stationary gear plate 96, gear 86 rotates about crank pin 88 when pin 88 is rotated by bevel gear 90. The pitch diameter

65 70 gear plate 96, gear 86 rotates about crank pin 88 when pin 88 is rotated by bevel gear 90. The pitch diameter

and circumference of the gear 86 in relation to the stationary ring gear teeth 98 is such that during each one-half revolution of bevel gear 90, gear 86 and bar 80 will rotate 180°. Since the roller 76 carried by bar 80 is mounted in the track 74 in transverse bar 68, the first 180° turn of gear 86 and bar 80 effects a horizontal and longitudinal forward movement of the transverse bar 68. The ends of bar 68, therefore, slidably engage and are guided by the inner side edges 102 of the bed plate 46. The second 180° turn of gear 86 and bar 80 moves the transverse bar 68 back to its original starting position. Since transverse bar 68 is connected to horizontal rods 66, rods 66 will likewise have horizontal reciprocating motion imparted thereto.

Each horizontal rod 66 carries a pair of gripper fingers 64 consisting of an upper jaw 104 secured to rod 66 and a lower jaw 106 loosely mounted on rod 66. Jaw 106 is engaged by one end of a torsion spring 108 the other end of which is anchored to a suitable collar 110 secured to the rod 66. The torsion spring 108 is employed for the purpose of urging lower jaw 106 into closed position against the upper jaw 104.

The opening of jaws 104 and 106 is effected by means of a jaw activating pin 112 (Figures 7 and 8). Pin 112 is slidably supported and carried in a horizontal hole or bore 114 of a lug 116 integral with and extending from the hub of the lower jaw 106. Pin 112 is provided with a conical step 118 (Figure 8) and an extension 120 which is of a lesser diameter than the pin 112. Integral with and extending from the hub of the upper jaw 104 is a lug 122 which is provided with a hole or bore 124 which is of the same diameter as the bore 114 of lug 116 of jaw 106. The end of hole 124 of lug 122 which faces the hole 114 of lug 116 is provided with a suitably tapered portion 126 whose taper corresponds to that of the conical step 118 of pin 112.

As illustrated in the drawings, Figures 7 and 8, lug 116 of jaw 106 is in sliding engagement with lug 122 of jaw 104. However, the holes 114 and 124 of the respective lugs are off-set to each other such that pin 112, pushed from the rear or from the left as viewed in Figure 8, would by means of its conical step 118 slide onto the tapered portion 126 and then into the hole 124 of the lug 122 of stationary jaw 104. Since jaw 106 is loosely mounted on rod 66 and hole 124 in the lug of stationary jaw 104 is slightly higher than entry of the pin 112 into hole 124 causes a vertical displacement or lifting of lug 116 of the swingable jaw 106. This, in turn, effects a downward movement and a disengagement of jaw 106 from the stationary jaw 104, against the action of spring 108, thus opening jaws 104 and 106.

The extension 120 of pin 112, of course, now projects beyond lug 122 and pressure applied against the end of extension 120 would cause pin 112 to slide out of the hole 124 of lug 122 of the stationary jaw 104. When this occurs, the torsion spring 108 acting upon the pivoted jaw 106 returns jaw 106 into engagement with stationary jaw 104. This return of jaw 106 causes a downward movement of lug 116, bringing the hole 114 of lug 116 again out of alignment with hole 124 of lug 122 as illustrated in Figure 8.

The movement of pins 112 within the lugs 116 and 122 is accomplished in the following manner. Each pair of jaws 64 is carried by a horizontal rod 66. Both rods 66, through the action of transverse bar 68, are reciprocated in the manner described herein above. Each of the bearing lugs 70 hold an adjustable pin activating screw 128 (Figures 1 and 3) projecting horizontally from its associated lug 70 and into the path of the pin 112 carried by the respective lug 116. During the forward movement of rods 66, gripper fingers 64 are in closed position and pin 112 projects from the lug 116 of its respective jaw 106 as illustrated in Figure 8. When rods 66 almost reach the end of their forward stroke, the protruding end of each pin 112 is engaged by one

of the screws 128. As gripper fingers 64 and rods 66 are still moved forward a short distance, screw 128 forces each pin 112 into hole 124 of lug 122, thereby effecting a downward movement of jaw 106 and opening of the gripper fingers 64.

Upon the return stroke of rods 66, gripper fingers 64 remain open with the extension 120 of each pin 112 projecting from the hole 124 of each respective lug 122. Shortly before the completion of the return stroke of rods 66, the projecting extension 120 of pins 112, contact the end face of bed plate 46. As rods 66 and fingers 64 continue to move the distance necessary to complete the return stroke, pins 112 are pushed by plate 46 out of holes 124 of lugs 122, thereby effecting a closing of the gripper fingers 64.

The reciprocating gripper fingers 64 are employed to pull the leading end of the cigar wrapping material web W into the path of travel of a cigar C into a pocket P of a turret T of a cigar wrapping machine of type; for example, as shown and described in my Patent No. 1,899,-174. Since the pulling of the web W by gripper fingers 64 is intermittent and the feeding of web W from the reel by feed rollers 48 and 50 is continuous, a loop L of web is formed (Figure 2). However, the web which forms a loop L provides the amount of web engaged by gripper fingers 64, the leading end of this web being positioned over the pocket P of the wrapping machine turret. The leading end of the wrapper web W is engaged and gripped by the gripper fingers 64 when rods 66 approach the end face of bed plate 46. Upon the return stroke of rods 66 fingers 64 operate to pull the web over the pocket P of the wrapping machine turret. When, at the end of the return stroke, pins 112 of the gripper fingers 64 engage the screws 128 the jaws of the gripper fingers open and release the web. Immediately after the web is released, that portion of the web which was pulled over the pocket by the gripper fingers 64 is severed from the rest of said web and a descending plunger plate 130 pushes a cigar and the cut length of wrapper web into the waiting pocket P of the wrapping machine turret.

The cutting of the web W is accomplished by the co-ordinated vertical movements of a V-shaped cutter plate 132 and a V-shaped ledger plate 134 (Figure 2). The ledger plate 134 is slidably confined in a track (not shown) formed in two spaced upright lugs 136 which project from and are preferably integral with the bed plate 46. The lower portion of ledger plate 134 is provided with a horizontal V-shaped cut-out 138. The upper central portion of plate 134 is provided with a narrow vertical slot 140, in which is freely mounted a horizontal stud 142 (Figure 2) carried by and projecting from the cutter plate 132. Thus cutter plate 132 is in sliding engagement with the ledger plate 134 and is held yielding against the front face of plate 134 by means of a tension spring 144. Spring 144 is positioned about stud 142 and confined between a nut 146 mounted on stud 142 and a washer 148 which bridges slot 140 and is in yielding contact with the rear face of ledger plate 134. Lugs 150 and 152 respectively are secured to the upper ends of cutter plate 132 and ledger plate 134, respectively. Lug 150 is connected by means of a line 154 to a rocker arm 156 mounted on an oscillating shaft 158 supported in suitable bearings in the upright lugs 136. To shaft 158 is secured an arm 160 which by means of a link 162 (Figures 1, 3 and 6) is connected to an arm 164 loosely mounted on and supported by a stud 166 held by and projecting from a vertical flange of the gear plate 96. Integral with the hub of arm 164 is a cam lever 168 (Figure 1), carrying, at its free end, a cam roller 170 (Figures 1 and 4) mounted in track 172 of a drum cam 174 secured to the continuously driven cam shaft 34.

Integral with the hub of rocker arm 156 but extending in the opposite direction is a short arm 176 (Figures

1, 2 and 3), the free end of which is connected by means of a link 178 to lug 152 on ledger plate 134. The free end of rocker arm 156 is provided with an open slot 180 in which is freely mounted the shank of a suitable stud 182. Stud 182 is mounted on and projects from the upper end of a vertical plunger rod 184 which is slidably mounted in a vertical guide track 186 of bracket 188 extending from and secured to the upright lugs 136. To the lower end of plunger rod 184 is secured the plunger plate 130.

In operation the rotation of drum cam 174, through cam lever 168, arm 164, link 162, arm 160 and shaft 158, effects an upward and downward motion of rocker arm 156. Since arm 176 is integral with rocker arm 156, a downward motion of the arm 156 causes an upward motion of arm 176. Further since cutter plate 132 is connected by means of link 154 to rocker arm 156 and ledger plate 134 is connected by means of link 178 to arm 176, a downward motion of rocker arm 156 causes a downward motion of cutter plate 132 and an upward motion of the ledger plate 134, thereby cutting the wrapping material web W positioned therebetween.

Simultaneously with the cutting of the wrapper web W, plunger plate 130, carried by the lower end of plunger 184, engages a cigar which has been fed into the path of plunger plate 130. Plate 130, upon continued downward motion of rocker arm 156, presses the engaged cigar and the cut wrapper blank A into the pocket P of the wrapping machine turret T.

In order to provide each wrapper blank with a combined cigar band and tear strip before being cut from the web W a wide tear strip band web S having a heat energizable thermoplastic coating and provided with regularly recurring printed patterns D thereon, is fed intermittently to a position where a predetermined narrow strip B is cut therefrom, and heat sealed to the wrapper web W passing beneath (Figure 2). Web S preferably is substantially the same width as wrapper web W. It may be wider, however, if it is desired to provide a composite cigar band-package opening tear strip which extends beyond the longitudinal sealed edge of the package.

The tear strip band web S is pulled intermittently from a suitable reel (not shown) by means of intermittently rotating upper and lower feed rollers 190 and 192 respectively. The upper feed roller 190 is mounted on a shaft 194 supported by a pair of spring loaded bearing blocks 196 (Figure 1). Blocks 196 are slidably confined in suitable slots in a pair of bearing brackets 198 adjustably mounted to the top side of bedplate 46. The lower feed roller 192 is secured to a shaft 200 rotatably supported in suitable bearings in bracket 198. Shaft 194 of the upper feed roller 190 and shaft 200 of the lower feed roller 192 are connected to each other by means of a pair of gears 202 (Figure 3). Further, shaft 200 rotatably supports a gear 204 (Figure 1), the hub of which is provided with a flange 206 (Figure 3) which normally engages with a friction ring 208. Ring 208 is secured to a flange 210 of a reel-shaped feed control member 212, slidably keyed in the end portion of shaft 200. The end of shaft 200 is provided with a head 214 and a tension spring 216 encircling shaft 210 and confined between head 214 and a stepped bore 218 in the hub of member 212. Spring 216 thus keeps the flange 210 of member 212 in engagement with the flange 206 of the gear 204. Gear 204 is engaged and oscillated by a horizontal gear rack 220 (Figure 1). Rack 220, at one end, is pivotally connected to the free end of a cam lever 222. Cam lever 222 is loosely mounted on a stud shaft 224 adjustably secured to a bracket 226 mounted on frame 24. Cam lever 222 carries a cam roller 228 (Figures 1 and 4) which is mounted in a cam track 230 of a drum cam 232 mounted on cam shaft 34. The gear rack 220 is slidably supported in a slot of housing 234, the upper portion of which also serves as a cover for

the gear 204. Housing 234 is secured to a suitable lug extending from one of the bearing brackets 198.

To control the intermittent feeding of the tear strip band web S there is provided a photoelectric registering device E which consists of a photo electric cell 236 (Figure 2) mounted in a slotted housing 238. Housing 238 is adjustably secured above the path of travel of web S, on an upright lug 240 extending from one side of the bridge bracket 62. A source of light 242, suitably designed to work with the photo electric cell 236, is located in a recess 244 in bridge bracket 62 beneath the path of web S and in vertical line with the photo-electric cell 236. Photo-electric cell 236 is connected to a conventional amplifier and control circuit 246 (Figure 3) which operates a relay 248. Relay 248, in turn, is connected to an electro-magnet 250 secured to a plate 252 and adjacent a circular flange 254 of the reel shaped feed control member 212. The magnet-supporting plate 252 is supported by a pair of horizontal rods 256 held by and extending from a suitable lug of one of the bearing brackets 198.

The feeding of the tear strip band web S is accomplished when the gear rack 220 is moved by means of cam lever 222 to the right as viewed in Figure 1, causing a counter-clockwise rotation of gear 204. Since flange 206 of gear 204 is in contact with the flange 210 of the control member 212, member 212, being slidably keyed to the shaft 200, effects rotation of shaft 200. This consequently rotates the lower feed roller 192 which is mounted on shaft 200. Since the lower feed roller shaft 200 is connected to the upper feed roller shaft 194, both feed rollers 200 and 194 are rotated, feeding tear strip band web S.

Proper registration is accomplished when predetermined spot or indicium X on the cigar band pattern D passes beneath the photoelectric cell 236. When this occurs, cell 236 effects an energization through the amplifier circuit 246 of the relay 248 closing contacts 258 thereof. This in turn completes a circuit energizing electro-magnet 250. Magnet 250 now magnetically attracts the flange 254 of the feed control member 212, causing member 212 to move along shaft 200 until its flange 254 is engaged by magnet 250. Flange 210 is thus disengaged from flange 206 of oscillating gear 204. Since gear 204 is the driving source of feed rollers 192 and 190, the feed of strip band web S is interrupted, even though gear 204 may still continue to be rotated by gear rack 220.

As soon as the band pattern D is thus properly registered and the feed of web S interrupted, a descending V-shaped knife blade 260 cuts a narrow strip B from the registered leading end of web S. As strip B is cut, a pair of spaced heated fingers 262 push strip B downwardly onto the then stationary wrapper material web W. Fingers 262 energize the thermoplastic coating of strip B and heat-seal strip B to web W, while simultaneously the leading end of web W is engaged by the gripper fingers 64.

The knife blade 260 operates in conjunction with a pair of guide plates 264 (Figure 2) which act as guide and ledger plates. The upper portion of knife blade 260 is secured to a pair of studs 266 which are pivotally supported by a pair of arms 268. Arms 268 are mounted on horizontal shaft 270 rotatably supported suitably in bearing brackets 198. One of the knife blades supporting studs 266 is pivotally connected by means of a link 272 to the free end of an arm 274. An arm 274 in turn is secured to an oscillating horizontal shaft 276 rotatably supported in bearing lugs 278 (Figures 1, 2 and 3). To one end of shaft 276 is secured an actuating lever 280 whose free end is connected to the cam lever 168 by means of an adjustable link 282 (Figure 1). The cam lever 168, through link 282 and arm 280, imparts oscillating motion to the shaft 274 which, in turn, effects vertical up and down cutting motion to knife blade 260.

To shaft 276 are also secured the heated fingers 262 which, are actuated synchronously with the movement of the knife blade 260. A central hub 284 which connects fingers 262 carries a suitable heating element 286 employed to supply the proper heat to fingers 262.

After the tear strip band B is cut from the web S and heat sealed in two spots onto the wrapping material web W, the leading end of web W is pulled by means of the reciprocating gripper fingers 64 across a pocket P of the wrapping machine turret T as described heretofore, and a predetermined length is cut therefrom which represents the wrapper blank A shown in Figure 11. While web W is pulled over pocket P, a row of cigars to be wrapped is advanced on a slotted supporting table 288 (Figures 3 and 6) by means of two pairs of oscillating walking beams 290. The cigars are advanced in such a manner that the leading cigar C is slightly pressed lengthwise against a stop and aligning plate 292, holding cigar C in the path of the plunger plate 130. Plate 130 as it travels downwardly with the web cutter plate 132 as described heretofore contacts the top side of cigar C as wrapper blank A is cut from the leading end of the wrapper material web W. The continued downward travel of plunger plate 130 then presses cigar C and the wrapper blank A which has been fed therebeneath into pocket P of the wrapping machine turret T.

The oscillating walking beams 290, are properly timed with the other mechanisms of the machine such that the rows of cigars on the table 288 are laterally advanced by beams 290 a distance equal to the width of a cigar. The stop and aligning plate 292 is suspended from and suitably secured to the bracket 188. The pocket P of the wrapping machine turret T may be substantially of the same construction and design as shown and described in my Patent 1,899,174. The bottom wall of the turret pocket P is formed by a plunger 294 yielding supported by a suitable spring 296 which is provided for the purpose of normally urging plunger 294 into its outermost radial position when not held down by a cigar inserted in pocket P.

The side walls of each pocket P are formed of a stationary jaw 298 and a movable jaw 300 (Figures 6 and 9). While the stationary jaw 298 is an integral part of the turret body 302, the movable jaw 300 is carried by the free ends of a pair of arms 304 pivotally mounted on a stud 306 (Figures 2 and 6) mounted on the turret body 302. One of the arms 304 is integral with a cam lug 308 which, at its free end, carries a cam roller 310 which contacts a cam 312 loosely mounted on shaft 30. Cam 312 receives rocking motion from a cam arm 314 (Figure 6) integral with and projecting from the hub of cam 312 and carrying at its free end a cam roller 316 which engages a cam track 318 of a cam 320 mounted on a shaft 322 supported in a suitable bearing of frame 24. Shaft 322 is driven by means of a gear 326 (Figure 3) keyed to the shaft 30. Cam 312 is rocked through cam track 318 and arm 314 for the purpose of effecting a quick closing of the jaw 300 after a cigar C and wrapper blank A have been inserted in the pocket by plunger plate 130, as described hereinabove.

To assure continuous contact of the cam roller 310 with cam 312, each pair of arms 304 is provided with a tension spring 315 (Figure 6). After the wrapper blank A and cigar C are pushed in a pocket P, the wrapper blank A covers three sides of the cigar, namely, the two sides and the bottom thereof, thus forming a U-shaped envelope with the two side flaps of wrapper blank A projecting straight up and out of pocket P. The first side flap is folded over the top side of the cigar by means of an oscillating and suitably curved folder plate 328 (Figures 3, 6 and 9) as illustrated in Figure 9. Folder plate 328 is secured to the free end of an arm 330 which is loosely mounted on shaft 30. Integral with arm 330 and projecting therefrom is a cam lever 332 which carries

5 a cam roller 334 running in a suitable track 336 (Figures 1 and 6) in cam 320. To the top of the folder plate 328, coinciding with the location of the tear strip band B on the wrapper blank A, is secured a knife blade 338 which is provided with two spaced knife points 340 (Figures 3 and 9) which project from a suitable step in the leading edge of folder plate 328. Points 340 are aligned with a pair of suitable slots in a ledger plate 342 mounted on top and towards the forward edge of a stationary semi-circular folder and retainer plate 344. Plate 344 encircles the wrapper turret T for approximately 180°, starting from the inserting station in a counter-clockwise direction, as illustrated in Figures 6 and 9.

10 As mentioned above, after a cigar C and wrapper blank A are inserted in pocket P, the top folder plate 328 swings in a counter-clockwise direction and effects a folding of one of the upstanding side flaps of the wrapper blank over the top side of the cigar. The two spaced knife points 340, coacting with the two slots in the stationary ledger plate 342, pierce the other side flap of the wrapper blank which at this time is held upright by the top forward end of the circular stationary folder and retainer plate 344 as illustrated in Figure 9.

15 As the turret T is indexed and the cigar carrying pocket P is advanced to the next station, the upstanding side flap of the wrapper blank is folded onto the already folded flap by the stationary folder and retainer plate 344. At the same time, the edges of the side flap are slotted by the knife points 340 as the flap is dragged down over the front edge of plate 344 due to the movement of the turret.

20 The wrapping machine turret T, has a plurality of pockets P and is constructed and driven intermittently in substantially the same manner as illustrated in my Patent 1,899,174. Adjacent turret T are suitably mounted end folding and sealing devices (not shown) arranged at different stations to effect a complete envelopment of the cigars. Since the top fold is slotted adjacent the tear strip band B as described heretofore, an easy removal of the wrapper material is assured by simply pulling at its slotted edge.

25 I claim:

1. In apparatus for supplying individual wrappers to a packaging machine, each of said wrappers having a tear tape applied thereto, the combination of an elongated bed, means for continuously feeding a continuous wrapper web to one end of said bed, driven gripper means mounted adjacent to the other end of said bed for intermittently feeding said wrapper web across said bed through a tear tape applying station and a cutting station, means for feeding a continuous tear tape web to said tear tape applying station along substantially the same line of travel as said wrapper web and in overlying relationship therewith, said tear tape web having substantially the same width as said wrapper web, cutting means mounted in said tear tape applying station for severing a band of tear tape from the leading edge of said tear tape web, means for adhering said band transversely on said wrapper web and substantially co-extensive with the width thereof, and cutting means disposed in said cutting station for severing from the leading edge of said wrapper web an individual wrapper having a band of tear tape applied thereto, said gripper means being operative to deliver said individual wrapper to the packaging machine.

2. The invention as defined in claim 1 wherein said gripper means includes a pair of gripper members, said gripper means being reciprocable whereby said gripper members engage the leading edge of said wrapper web for pulling said web across said bed, said cutting means in said cutting station being operative to sever said wrapper web after a predetermined length of said wrapper web passes through said cutting station.

3. The invention as defined in claim 1 wherein said tear tape web is provided with regularly recurring spaced patterns, registering indicium for each of said patterns, a photo-electric device for detecting said registering indicia,

means operative in response to said photo-electric device detecting a registering indicium to interrupt the feed of said tear tape web whereby each band is provided with a complete pattern disposed in pre-determined position on said wrapper web.

4. Mechanism for supplying individual wrappers to a cigar packaging machine, said wrappers having a band of tear tape applied thereto, comprising a source of supply of continuous thermoplastic wrapper web, a pair of gripper fingers for engaging the leading edge of said wrapper web at a web-engaging station, means mounting said gripper fingers for movement into and out of gripping engagement with said leading edge of said wrapper web and to and from said web-engaging station, means for moving said gripper fingers, a source of supply of continuous tear tape web, provided with a heat-energizable thermoplastic coating, said tear tape web having regularly recurring printed patterns thereon, a registering indicium for each of said patterns, a pair of intermittently driven feeding rollers for intermittently feeding said tear tape web, said tear tape web being fed along the same line of travel and in overlying relationship with said wrapper web, a photo-electric detecting device for detecting the feeding of said registering indicia to a pre-determined position on their path of travel, an electro-magnet, an operating circuit connecting said photo-electric device to said electro-magnet for selectively energizing said electro-magnet when a registering indicium has been fed to said predetermined position, means operatively associating said electro-magnet with said tear tape feeding rollers whereby said energized electro-magnet is operative to interrupt the feeding of said tear tape web, a knife, means mounting said knife for severing a short length from the leading edge of said tear tape web after said tear tape web feed has been interrupted, said severed short length of tear tape having a complete pattern disposed thereon, spaced heater fingers, means mounting said heater fingers for engagement with said short length of severed tape, said heater finger being operative to heat seal said severed tape onto the upper surface of said continuous wrapper web, said tear tape being located in pre-determined position on said wrapper web and substantially co-extensive with the width thereof, said gripper fingers being adapted to engage the leading edge of said wrapper web with a tear tape applied thereto and deliver a pre-determined length of wrapper web to a wrapping station remote from said web-engaging station, means for severing said pre-determined length from said wrapper web, and means for delivering said severed wrapper to the cigar packaging machine.

5. In apparatus for wrapping cigars in individual wrappers having a tear tape applied thereto, the combination of a source of supply of continuous thermoplastic wrapper web, a pair of gripper fingers for engaging the leading edge of said wrapper web at a web-engaging station, means mounting said gripper fingers for movement into and out of gripping engagement with said leading edge of said wrapper web and to and from said web-engaging station, means for moving said gripper fingers, a source of supply of continuous tear tape web, provided with a heat-energizable thermoplastic coating, said tear tape web having regularly recurring printed patterns thereon, a registering indicium for each of said patterns, a pair of intermittently driven feeding rollers for intermittently feeding said tear tape web, said tear tape web being fed along the same line of travel and in overlying relationship with said wrapper web, a photo-electric detecting device for detecting the feeding of said registering indicia to a predetermined position on their path of travel, an electro-magnet, an operating circuit connecting said photo-electric device to said electro-magnet for selectively energizing said electro-magnet when a registering indicium has been fed to said predetermined position, means operatively associating said electro-magnet with said tear tape feeding rollers whereby said energized electro-mag-

net is operative to interrupt the feeding of said tear tape web, a knife, means mounting said knife for severing a short length from the leading edge of said tear tape web after said tear tape web feed has been interrupted, said severed short length of tear tape having a complete pattern disposed thereon, spaced heater fingers, means mounting said heater fingers for engagement with said short length of severed tape, said heater finger being operative to heat seal said severed tape onto the upper surface of said continuous wrapper web, said tear tape being located in predetermined position on said wrapper web and substantially co-extensive with the width thereof, said gripper fingers being adapted to engage the leading edge of said wrapper web with a tear tape applied thereto and deliver a predetermined length of wrapper web to a wrapping station remote from said web-engaging station, means for severing said predetermined length from said wrapper web, said severed wrapper being located in a selected position at said wrapping station, a source of supply of cigars, means for feeding said cigars serially to said wrapping station, said cigar feeding means being adapted to position a cigar in overlying relationship with said severed wrapper, the major axis of said cigar substantially coinciding with the major axis of said severed wrapper, a wrapping turret having a plurality of pockets and adapted to be moved stepwise through a plurality of operating stations, a plunger, means mounting said plunger for movement against a cigar positioned on a severed wrapper, means for operating said plunger to move a cigar and wrapper into a pocket of said wrapping turret indexed to said wrapping station, the marginal edges of said severed wrapper being folded into overlying relationship with each other as a filled pocket is indexed away from said wrapping station to envelope said cigar in said pocket, and means for weakening a wrapper adjacent to its associated tear tape as a wrapper and cigar in a pocket are indexed away from said wrapping station to facilitate unwrapping of said cigar by the user.

40 6. The invention as defined in claim 4 wherein each pair of said gripper fingers includes a stationary finger and a movable finger, a stud mounting said fingers in common adjacent the non-gripping ends thereof, each of said fingers having an aperture in its non-gripping end, 45 said aperture in said movable finger being offset relative to said aperture in said stationary finger, resilient means normally urging said fingers into closed position, an elongated member provided with cam surfaces adjacent the mid-point thereof, means slidably mounting said 50 member in said apertures, means for selectively sliding said elongated member in said apertures in one direction at said wrapping station, said cam surfaces being adapted to align said offset apertures to urge said gripper fingers into open position at said wrapping station and means for 55 sliding said elongated member in the opposite direction at said web-engaging station, said resilient means being operative at said web-engaging station to close said fingers urged into open position at said wrapping station whereby said gripper fingers are moved out of and into engagement with the leading edge of said wrapper web.

60 7. The invention as defined in claim 4 including a pair of spaced operating rods, means mounting one of said pairs of gripper fingers on one of said operating rods, means mounting said spaced operating rods for reciprocating movement to and from said web-engaging station to and from said wrapping station, means for reciprocating said spaced rods comprising an activating bar, means operatively associating said activating bar with said spaced operating rods at one end of said spaced rods, a stationary circular gear, a travelling gear meshing with and travelling along said stationary gear, means for moving said travel gear along said circular gear and means connecting said travelling gear to said activating bar whereby said bar is travelled first in one direction as said travelling gear is moved along one half of said

stationary gear and then in the opposite direction as said travelling gear is moved along the other half of said stationary gear, thereby imparting reciprocating movement to said activating bar and said operating rods.

8. The invention as defined in claim 5 wherein said weakening means includes spaced cutting devices, means mounting said cutting devices for movement peripherally of said turret at said wrapping station against a marginal edge of a wrapper partially enveloping a cigar inserted into a pocket at said wrapping station, means for moving said cutting devices in timed relationship with the movement of said pocket away from said wrapping station whereby said cutting devices are operative to pierce said wrapper as said marginal edges thereof are folded into overlying relationship.

9. In apparatus for packaging elongated articles in individual wrappers having a tear tape applied thereto, the combination of a source of supply of continuous wrapper web, means for intermittently feeding said wrapper web, a source of supply of continuous tear tape web, said tear tape web being of substantially the same width as said wrapper web, means for feeding said tear tape web intermittently in timed relationship with the feeding of said wrapper web, said tear tape web being fed along the same line of travel as said wrapper web and in overlying relationship therewith, means for severing a short length from the leading edge of said tear tape web, means for adhering said short length transversely on said wrap-

5 per web and substantially co-extensive with the width thereof, said wrapper web feeding means being adapted to feed a predetermined length of wrapper web with a tear tape thereon, means for severing said predetermined length from the leading edge of said wrapper web, means for supplying an individual article to said severed wrapper, means for folding the margins of said severed wrapper into overlying relationship with each other to envelope said article delivered thereto, and means for 10 weakening said folded wrapper adjacent to its associated tear tape to facilitate unwrapping of said article by a user, said weakening means including spaced cutting devices, means mounting said cutting devices for movement against a marginal edge of a severed wrapper partially enveloping an article, and means for moving said cutting devices in timed relationship with said folding means whereby said cutting devices are operative to pierce said severed wrapper as the margins thereof are folded into overlying relationship to envelope said article.
